CENTRIFUGAL CASTING MACHINE

Jeremias H. Ledebuur, Beverwijk, Netherlands,
assignor to Koninklijke Nederlandsche Hoog-
ovens en Staalfabrieken N. V., IJmuiden,
Netherlands, a company of the Netherlands

Application February 17, 1934, Serial No. 711,775
In the Netherlands February 21, 1933

6 Claims. (Cl. 22—65)

This invention relates to certain new and useful improvements in centrifugal casting machines and more particularly to machines of the type for producing relatively long cylindrical castings in refractory lined molds or flasks.

Machines of this type as hitherto used are as a rule so arranged that the mold is supported intermediate its ends in two spaced places by supporting rollers and is adapted through a magnetic clutch, to be driven at one end only or to be driven by the supporting rollers themselves. Driving the mold at one end only has the disadvantage that it is hardly possible to ensure correct alignment of the driving shaft and the axis of the mold supported by the said rollers, which mold may have various diameters. In this respect, driving the mold through the supporting rollers has marked advantages, although it is a drawback of last said construction that the rollers and the races therefore are liable to unequal wear and tear and are difficult to clean, which interferes with the correct rotation of the mold and, consequently, with the quality of the casting.

The present invention has for its object to obviate said disadvantages. With this object in view, the mold is not supported intermediate its ends by rollers, but exclusively at both ends, on the one side by a drive shaft rigidly supported in two or more bearings so as to occupy an invariable position, at the other end by a revoluble head through which the molten metal can be poured into the mold, said head being supported by a pedestal through a ball bearing or the like encircling the mold engaging surfaces or surfaces of the revoluble head and located substantially in the same vertical plane at right angles to the axis of rotation.

In this manner the mold is supported at both ends so that no vibratory motion can be set up therein during the casting and, as a consequence thereof, after the casting operation or during the solidification of the cast metal, notwithstanding the considerable centrifugal forces resulting, for instance, from unsymmetrical lining or distortion of the mold. This favorably affects the operation and the life of the machine, and also the quality of the castings.

The driving head and also the driven head may be associated either with a movable head stock, or with a fast head stock, that is to say, it may be rigidly secured to the foundation, or be adapted for axial displacement to enable the insertion and the removal of the molds. Irrespective thereof, the driving head may be

adapted for axial displacement to enable the casting of pipe or the like of various lengths, when the driven head and the pouring trough or spout with associate parts may remain stationary.

With a driven or casting head arranged as stated above, the ball bearing provided thereon is not too much exposed to the radiant heat of the molten metal in the ladle, the spout and the mold, especially not if the mold itself, or a member forming in effect a continuation thereof, is arranged to project from the driven head and the fast head stock is fitted with a shield or diaphragm for checking the radiant heat of the molten metal and of the ladle. Such a diaphragm may also be fitted to the driving head or to the core for the bell end of the pipe, or the said core may be made so as to completely close the mold at said end.

To also reduce the rate of heat transference by conduction from the mold to the ball bearing, the surface of the driven head, designed to engage frictionally with a corresponding surface on the mold, instead of being continuous may be interrupted so as to engage the mold through a small area only. A similar construction may be used in connection with the driving head. With the same object in view, the projections or lugs through which the heads engage the mold may be of volute or impeller form, or fins of said form may be provided intermediate the lugs, so that during rotation of the mold and after the casting air is caused to flow through the gap or gaps between the mold and the heads. Under these conditions, said head cannot be excessively heated by the hot mold. On the side of the driving head the current of cooling fluid may be forced into and through the mold so as to influence the rate of cooling and consequently the quality of the casting. In order to produce a very strong current of cooling fluid for the last said purpose, the driving head may be provided also on the other side with apertures and impeller fins, or said apertures may be enclosed by a stationary case connected to a compressed air or other gas supply pipe.

In order that a fresh mold may be readily inserted, and that minor inaccuracies in the assemblage of the various parts of the machine may be compensated for, the bearing of the driven head, if fitted in a movable head stock, may be arranged for oscillation about horizontal trunnions in a yoke adapted for swinging motion about a fixed axis in parallel relation with said trunnions and engaged by hydraulic or

pneumatic means whereby the driven head may be forced into frictional engagement with the mold.

With this construction and when the mold is heated so as to expand, the driven head is adapted to yield against a constant pressure, during which movement the said head remains parallel with itself at a substantially constant level, and consequently in correct engagement with the mold.

With a view to possible damage and in order that pipe or the like of different diameters may be cast, the ball or like bearing (or the Michell bearing that may be used if the pipe has a large diameter and must be rotated at a very high speed), as well as the parts which directly engage the mold may be arranged to be readily exchangeable. The same applies to the driving head.

The annexed drawings serve to further illustrate the invention.

Fig. 1 is a more or less diagrammatic side view of a centrifugal casting machine in which the driven head is provided in a fast head stock and the driving head in a sliding head stock or carriage.

Fig. 2 is a cross-sectional view along the line II—II in Fig. 1, on an enlarged scale.

Figs. 3, 4, and 5 are a side elevational view partly in section, a front view, and a sectional view along the line V—V in Fig. 3, respectively, of a driven head provided in a movable head stock.

Figs. 6 and 7 illustrate axial sectional views of driving heads of different construction.

The mold 1 (Fig. 1) is provided with reinforcing rings 2, and formed on either end with a taper outer surface adapted to engage frictionally with corresponding taper inner surfaces of the heads 3 and 4 of the casting machine.

The head 3 is secured to the free end of a shaft 5 journaled in bearings 6 and coupled through a magnetic clutch 7 with an electromotor 8. The bearings and the motor are mounted on a slide 9 supported by a second slide 10, which in turn is supported by a bed plate 11 secured to the foundation (Fig. 2).

The slides 9 and 10 are interconnected by a double acting hydraulic cylinder 12, which is secured to the slide 10, and through a hydraulic plunger 13, the rod 14 of which engages the slide 9. When the slide 10 is locked in position, the slide 9 is adapted under the action of hydraulic pressure to be moved forward, when the mold 1 is to be engaged between the heads 3 and 4. During the casting operation and the consequential heat expansion of the mold, the slide 9 is adapted to yield against the action of the hydraulic pressure on the plunger 13, while continuing to exert the required axial pressure on the mold 1.

Mounted in the slide 10 is a transverse shaft 15 provided outside the slide with a ratchet handle 16, and inside the slide with two pinions 17 meshing with racks 18 on the bed plate 11. By means of this arrangement the slide 10 is adapted, by manual force, to be axially displaced with respect to the bed 11 and to be moved into the required position responsive to the length of the mold. The slide 10 is further provided with strips 19 engaged by nuts on screw bolts 20, by means of which the slide 10 can be locked in position in such a manner as to allow the slide 9 to move to and fro.

The driven head (Fig. 1) consists of an an-

nular member 4 which is revoluble in a stationary sleeve 21 supported by a pedestal 22. The pouring trough or runner 23, which extends through said head, is illustrated in dash and dot lines, as well as the ladle 24 in its raised position.

In accordance with Figs. 3-5, the driven head 4 is fitted in a non-revolvable sleeve or annulus 25 provided on the rear side with a diaphragm 26 and on either lateral side with a trunnion 27 engaging a yoke 28 hinged as at 29 to brackets 30 of a pedestal 31. Pivotal mounted on said pedestal is a single acting hydraulic cylinder 32, the plunger 33 of which is adapted to engage the yoke 28. Coiled springs 34 are provided to connect the yoke 28 with the pedestal 31 so as to urge the yoke backward when the hydraulic plunger 33 is relieved from pressure. During this backward movement the yoke engages a projection 35 on the sleeve 25, so that said sleeve with the driven head 4, after disengaging the mold, occupies a position somewhat as shown in dash and dot lines in Fig. 3.

The driven head 4 of the mold is supported in the stationary sleeve 25 through a ball bearing 36, and is provided on its inner side with four lugs 37 each having a taper inner surface designed to engage frictionally with a corresponding conical outer surface 38 of the mold 1. Instead of conical, the last said surface may also be spherical, and the same applies to the opposite end of the mold. In the interstices between the lugs 37, the driven head 4 is provided with fins 39, which during rotation of said head and of the mold 1 produce a strong current of air between said elements, whereby those portions through which the heat of the mold is adapted to be transferred to the ball bearing are intensively cooled. If necessary, the cooling of the ball bearing can still be improved by ample forced lubrication thereof and by cooling of the returned oil, and if necessary also by water cooling of the sleeve 25.

The revolving parts are so arranged that they can be readily removed from the sleeve 25 and replaced by other parts, which may have different inner diameters.

Since in a machine as illustrated in Figs. 3-5 the driven head is hydraulically forced against the mold, said head may cooperate with a driving head in a fast head stock, which need be adapted for axial displacement only in case molds of various lengths are to be used. If a cast flask is to be charged out of the machine and a freshly lined mold is to be inserted, the driven head is swung backward and thereafter again swung forward by the outlet and the inlet of water from and into the cylinder 32.

The driving head in accordance with Fig. 6 acts as a fan or impeller since it is provided with apertures or passages with fins 40, by means of which a current of air is forced into the mold in the direction indicated by the arrows. This current of air also cools the driving head itself. Direct transference of heat from the mold 1 to the head 3 is minimized by the fact that the mold 1 is frictionally engaged only by a few lugs 41 of small height, so that the gaps between the head and the mold are relatively narrow and a small portion only of the air can escape through said gaps. A diaphragm 42 serves to prevent radiant heat of the hot metal from heating the driving head.

In accordance with Fig. 7, the driving head is provided with passages 43 not fitted with fins and enclosed on the outside by a stationary case 44.

connected to a compressed air or other gas supply pipe 45. Also by these means the required circulation of cooling fluid through the mold 1 can be produced. This arrangement requires a 5 separate source of compressed air or other gas, but has the advantage that the rate of flow can readily be controlled during operation. If desired, the compressed air or gas may be supplied through the hollow drive shaft.

10 In Figs. 6 and 7, the driving head is slid on a reduced end portion of the shaft 5 and secured thereto by means of a disc 47 with screw bolts 48, and prevented from rotation with respect to the shaft by means of a key 46. In this manner, the head can easily be detached from the shaft and replaced by another one with the same or with a different diameter. In order that the machine may operate satisfactorily, it is necessary for the driven head to be in accurate register 15 with the driving head. With this object in view, the non-revolute sleeve of the driven head may, after the erection of the machine, be trued up by means of a boring bar or spindle mounted in exactly concentric relation with the driving head.

20 Alternatively, before erecting the parts on the side of the pouring spout, an exact counterpart of the mold is secured to the driving head and suitably supported at its free end, whereupon the driven head with associate parts is suspended 25 from said free end and the pedestal is eventually secured in position to the foundation.

I claim:

1. A centrifugal casting machine for the manufacture of pipe and other cylindrical castings in refractory lined molds or flasks, comprising a driving head and a driven or casting head, a mold or flask axially clamped between said heads and supported thereby, a non-rotatable part rotatably supporting said driven head, a yoke rotatable about a fixed axis and supporting the said non-rotatable part, and yieldable means tending to urge said yoke into engagement with the mold.

2. A centrifugal casting machine for the manufacture of pipe and other cylindrical castings in refractory lined molds or flasks, comprising a driving head and a driven or casting head, a mold or flask axially clamped between said heads and 5 supported thereby, a non-rotatable part rotatably supporting said driven head, a yoke rotatable about a fixed axis and being pivotally connected to the said non-rotatable part, and yieldable means tending to urge said yoke into engagement- 10 with the mold.

3. In a machine as claimed in claim 1, a pedestal for supporting the shaft of the driving head with associated driving mechanism, a bed plate upon which said pedestal is adapted to be slid 15 axially, and mechanical means for moving said pedestal on said bed plate and for locking it relative thereto, to adapt the machine for casting pipes of different lengths.

4. A machine as claimed in claim 1 in which 20 at least one of said heads is provided with a plurality of projections each having a bearing surface, the mold or flask being provided with a complementary bearing surface.

5. A machine as claimed in claim 1, in which 25 at least one of the heads is provided with a circular series of projections each having a bearing surface and formed as a fin adapted during rotation of said head to act as a propeller, the mold or flask being provided with a bearing surface 30 complementary to the said surfaces of the projections.

6. A machine as claimed in claim 1, in which 35 at least one of the heads is provided with a circular series of projections each having a bearing surface, the mold or flask being provided with a complementary bearing surface, fin-shaped members being interposed between said projections to act as propellers adapted during rotation of said head to force fluid through the clearance between the mold and the head. 40

JEREMIAS H. LEDEBOER.
